[57] CLAIM

The ornamental design for the outdoor lighting fixture as
shown and described.

DESCRIPTION

FIG. 1 is a perspective view of an outdoor lighting fixture of the present invention which can be mounted on a pole or a wall;

FIG. 2 is a right side elevational view thereof;

FIG. 3 is a left side elevational view thereof;

FIG. 4 is a back elevational view thereof;

FIG. 5 is a front elevational view thereof;

FIG. 6 is a top plan view thereof;

FIG. 7 is a bottom plan view thereof;

FIG. 8 is a perspective view of a second embodiment of the outdoor lighting fixture;

FIG. 9 is a side elevational view thereof, the left and right sides being mirror images of each other;

FIG. 10 is a front elevational view thereof, the front and back sides being mirror images of each other;

FIG. 11 is a top plan view thereof;

FIG. 12 is bottom plan view thereof;

FIG. 13 is a perspective view of a third embodiment of the outdoor lighting fixture;

FIG. 14 is a front elevational view thereof;

FIG. 15 is a back elevational view thereof;

FIG. 16 is a right elevational view thereof;

FIG. 17 is a left elevational view thereof;

FIG. 18 is a top plan view thereof;

FIG. 19 is a bottom plan view thereof;

FIG. 20 is a perspective view of a fourth embodiment of the outdoor lighting fixture;

FIG. 21 is a front elevational view thereof, the front and back views being mirror images of each other;

FIG. 22 is side elevational view thereof, the left and right sides being mirror images of each other;

FIG. 23 is a top plan view thereof;

FIG. 24 is a bottom plan view thereof;

The broken lines are shown for illustrative purposes only
and form no part of the claimed design.
